Primary Examiner — Jonathan J Han*Assistant Examiner* — Amanda J Berlinski(74) *Attorney, Agent, or Firm* — Quarles & Brady LLP(57) **CLAIM**

The ornamental design for a medical instrument, as shown and described.

DESCRIPTION

FIG. 1 is an isometric view of a front, top, and right side of an ornamental design for a medical instrument;

FIG. 2 is a top plan view of the medical instrument of FIG. 1;

FIG. 3 is a right side elevational view of the medical instrument of FIG. 1;

FIG. 4 is a rear elevational view of the medical instrument of FIG. 1; and,

FIG. 5 is a front elevational view of the medical instrument of FIG. 1.
